(57) **CLAIM**

The ornamental design for a chaise lounge, as shown and described.

DESCRIPTION

FIG. 1 is a front perspective view of the chaise lounge of the present invention;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left-side elevational view thereof, the right-side elevational view being a mirror image thereof.

The fragmented depiction of a weave pattern is understood to repeat uniformly throughout the circumscribed area.
